UNITED STATES PATENT OFFICE.

LOUIS D. NADEL, OF EAST ORANGE, NEW JERSEY, ASSIGNOR TO FREDERICK M. PRESCOTT.

PHONOGRAPH MOTOR.

Application filed May 8, 1919. Serial No. 295,681.

To all whom it may concern:

Be it known that I, LOUIS D. NADEL, a citizen of the United States, and a resident of East Orange, in the county of Essex and 5 State of New Jersey, have invented an Improvement in Phonograph Motors, of which the following is a specification.

My invention relates generally to improvements in motors for phonographs. The 10 principal object of my invention is to provide an improved motor of this type embodying, among other features, improved transmission of power, improved supporting means, and improved spring spindle.

15 In the drawings accompanying this specification and forming a part thereof I have disclosed, for purpose of illustration, one embodiment which my invention may assume. In these drawings:

20 Figure 1 represents a top plan view of a phonograph motor embodying this illustrative form of my invention;

Figure 2 represents a side elevation of this motor.

25 Figure 3 represents a bottom view of the motor; and

Figure 4 is a detail showing the construction of my spring spindle.

In these drawings I have omitted for sake 30 of clearness the entire phonograph cabinet and associated parts, and I have also omitted many parts of the motor which are not a part of my invention and accordingly would confuse the drawings and in no way assist 35 in understanding my invention.

The entire phonograph motor is shown as mounted on a frame 11 which preferably consists of a flat top plate 12 having numerous depending lugs, two of which, 13 40 and 14, serve to support a fixed shaft 15. Mounted on this shaft 15 is a gear 16 having integral therewith a winding spindle 17 extending along the shaft 15. Starting at a point on the shaft 15 near the free 45 end of the spindle 17 is a drive spindle or drive shaft 18 rotatably mounted on the shaft 15 and having integral herewith a spiral drive gear 19. Mounted about the spindles 17 and 18 are two spring drums 20 and 21 50 each open at the end adjacent the other, and closed at the remote end. The remote end of the drum 20 is provided with a sleeve 22 which encircles the winding spindle 17 and acts as a bearing by means of which the drum 20 may rotate on the spindle 17.

The remote end of the drum 21 is provided with a similar sleeve 23 encircling the drive spindle 18 to provide for the rotation of the drum 21 on that spindle. Between the adjacent ends of these drums 20 and 21 is 60 placed a disk 24 provided with a beveled opening 25 which closely fits the shaft 15 between the adjacent and correspondingly beveled ends of the spindles 17 and 18. The drums 20 and 21 and the disk 24 are rigidly 65 secured together by means of screws 25' and rotate as a unit upon the shaft 15 and associated parts. Mounted between the spindle 17 and the drum 20 is a coil spring 57 having its inner end secured to the spindle 70 17 and its outer end secured to the inner surface of the drum 20. A similar spring 58 is mounted in the same way between the spindle 18 and the drum 21.

Particularly in Figure 4, I have illustrated the means which I prefer to employ in securing the inner end of the spring to the spindle, and have shown my securing means applied to the winding spindle 17 and the spring 57. The spindle 17 80 is provided with a flattened portion 26 from which rises a rivet 27 functioning to secure the inner end of the spring to the spindle, the spring being annealed to prevent breaking thereof at the corner where the flattened portion of the spindle merges into the cylindrical surface thereof. This rivet 27 is provided with a head 29 so formed as to lie along the cylindrical periphery of the spindle 17 and thus form with the body 90 of the spindle a circular drum on which the succeeding coils of the spring are wound.

Meshing with the gear 16 I have shown a gear 30 mounted on a winding shaft 31 extending beyond the side of the frame 11 and 95 formed interiorly with the usual screw threads for engagement by a detachable winding handle. The customary ratchet mechanism 32 is provided to prevent retrograde movement of the winding shaft.

I have illustrated a turntable shaft 33 mounted vertically in suitable bearings in the frame 11 and so positioned that the axis thereof intersects the axis of the winding shaft 31. Means are provided to transmit 100 the power from the drive shaft to the turntable shaft in a highly efficient manner and without appreciable noise, such means being herein shown as an intermediate shaft operatively connected to each of the other 110

shafts. I have illustrated this intermediate shaft 35 mounted in lugs 36 and 37 depending from the under surface of the frame 11 and supported at a substantial angle to both the power shaft and the turntable shaft, and in this particular embodiment I have found it convenient to make each angle approximately 45°. Connecting the intermediate shaft 35 with the drive shaft 18 is 10 a means for transmitting rotation from the drive shaft to the intermediate shaft, which is herein disclosed as a gear 19 mounted on the drive shaft 18, preferably spirally cut, and meshing with a co-operating pinion 34 mounted on the intermediate shaft 35. I have also provided means for connecting the intermediate shaft 35 with the turntable shaft 33 and this means is herein shown as a gear 38 mounted on the intermediate shaft 35, preferably spirally cut, and engaging with a co-operating pinion 59 secured to the turntable shaft.

The gear and pinion connecting the power shaft and the intermediate shaft and the gear 25 and pinion connecting the intermediate shaft and the turntable shaft have narrow faces as shown. The gears and pinions have faces of substantially equal width, i. e., of substantially equal extent in a direction parallel 30 to the shaft as distinguished from a worm and worm wheel drive in which the worm has a relatively long engaging face parallel to the shaft. By the term face is meant the cylindrical operative engaging portion of 35 the gear or pinion. This arrangement avoids the use of a long spiral gear or worm such as commonly used in phonographs and which are expensive to manufacture.

Connected to the turntable shaft 33 is a 40 suitable governor which may be of the type usually employed. This governor may comprise a worm gear 39 engaging a worm 40 mounted on a governor shaft 41 which is supported in bearings 42 and 43 carried respectively by lugs 44 and 45 depending from the frame 11. The bearing 42 is carried directly by the lug 44 but the bearing 43 is mounted in a strip 46 slidably secured in a groove in the lug 45 to permit adjustment 45 of this bearing 43 in a direction to move the worm toward or away from the worm gear and thus compensate for wearing down of the worm and worm gear. This strip 46 is secured to the block 45 by a set screw 47 extending through a slot in the strip 46 and threaded into the block 45. The strip 46 is moved along the block 45 by means of an adjusting screw 48 provided with a flange 49 which engages within a slot 50 in the strip 46 and thus transmits its longitudinal movement to the strip 46. It will be understood that the strip 46 cannot be moved when the set screw 47 has been tightened.

Mounted on the governor shaft and rigidly 65 secured thereto is a disk 51 to which are se-

cured two springs 52 each carrying a governor weight 53 and each secured at the remote end to a disk 54 which is slidable along the governor shaft 41. Positioned to engage with the disk 54 under certain circumstances is the usual brake 55 supported in a lug 56 on the lower side of the frame 11 and adapted to be adjusted from the upper side of the frame in the usual manner.

The entire frame of the phonograph is 75 mounted on a three-point suspension at the points 60, 61, and 62, which are substantially outside the lateral limits of the motor and are arranged symmetrically with respect to a plane perpendicular to the frame 80 11 and passing through the winding shaft 31 and the turntable shaft 33.

Assuming the usual stop to be set to prevent rotation of the turntable shaft 33 and consequently to prevent rotation of the intermediate shaft 35 and the drive spindle 18, rotation of the winding shaft 31 by the usual winding crank will cause a consequent rotation of the winding spindle 17 through the coaction of the gears 30 and 18, and this rotation of the spindle 17 will tend to coil up the spring 57. When the tension in the spring 57 has been increased in this manner to an amount somewhat greater than that in the spring 58 the entire spring barrel 20—21 will rotate under the influence of the spring 57 to rotate the outer end of spring 58 and thus produce a tension in the spring 58 equal to that in the spring 57. Continued rotation of the 95 winding shaft 31 will result in a continued tensioning of the springs 57 and 58 in this manner until both are fully wound. The ratchet 31 prevents reverse rotation of the 100 winding shaft and retains the springs in 105 tensioned condition. When the brake is removed from the turntable shaft 33 the spring 58 will cause rotation of the drive spindle 18 and the spiral gear 19 secured thereto, and after a certain amount of rotation of the drive spindle 18 under the action of spring 58, this spring will be appreciably weaker than the spring 57 and the latter will cause a rotation of the entire 110 spring barrel 20—21 to equalize the tension in the two springs. This equalization will take place continuously so long as the power shaft is permitted to rotate. Rotation of the spiral gear 19 will cause consequent rotation of the spiral pinion 34, the intermediate shaft 35, and the spiral gear 38 secured thereto. Rotation of the spiral gear 38 will cause rotation of the spiral pinion 59 on the turntable shaft 33 and consequent rotation of this shaft and the turntable mounted on this shaft. The speed of the turntable shaft is governed by the governor in the usual manner.

The transmission which I have described above not only conveys power from the 130

drive shaft to the turntable shaft in a highly efficient manner but also operates quietly and substantially noiselessly. The suspension which I have illustrated greatly facilitates adjustment of the frame in the cabinet to position the winding shaft and turntable shaft properly with regard to the apertures in the cabinet with which they are correlated. By the construction of 10 a spring spindle which I have herein illustrated I bring the extremity of the spring securing rivet into the cylindrical periphery of the spindle and thus wind my spring about a true cylinder and eliminate the 15 usual distortion of the spring and the point of high curvature resulting from this distortion. By removing this point of high curvature, I greatly reduce the tendency of the spring to snap off and by providing a 20 substantially cylindrical periphery I secure substantially even tension in the spring and eliminate the variations in tension due to the periodic variations in diameter which result from a securing means projecting 25 from the spring spindle.

There are uses for my motor and advantages therein other than those which have been specifically pointed out and there are embodiments and modifications other 30 than those herein illustrated. These uses, advantages, embodiments, and modifications are all embraced in my invention, especially as they may be included in the appended claims.

35 I claim:

1. A phonograph motor comprising a spring, a governor therefor, a winding shaft for tensioning said spring, a drive shaft arranged to be driven by said spring, 40 a turn table shaft disposed at substantially right angles to said drive shaft, a turn table carried thereby, an intermediate shaft disposed at a substantial angle to each of said shafts, a spiral gear on said drive shaft, a 45 spiral gear on said intermediate shaft meshing therewith, a second spiral gear on said intermediate shaft, and a spiral gear on said turn table shaft meshing with said second spiral gear.

50 2. A phonograph motor comprising a spring, winding means for tensioning said spring, a drive shaft arranged to be driven by said spring, a turn table shaft disposed at substantially right angles to said driving shaft, an intermediate shaft disposed at an angle of substantially 45 degrees to each of said shafts, a sliding and rolling connection transmitting rotation from said drive shaft to said intermediate shaft, and a sliding and 55 rolling connection transmitting rotation from said intermediate shaft to said turn table shaft.

3. A phonograph motor comprising a spring, winding means for tensioning said 60 spring, a drive shaft arranged to be driven

by said spring, a turn table shaft disposed at substantially right angles to said driving shaft, an intermediate shaft disposed at an angle of substantially 45 degrees to each of said shafts, a sliding and rolling connection transmitting rotation between said intermediate shaft and one of said other shafts, and means to transmit rotation between said intermediate shaft and the other of said shafts. 70 75

4. A phonograph motor comprising a spring, winding means for tensioning said spring, a drive shaft arranged to be driven by said spring, a turn table shaft disposed at substantially right angles to said driving shaft, an intermediate shaft disposed at a substantial angle to each of said other shafts, means for transmitting rotation from said drive shaft to said intermediate shaft, and means transmitting rotation from said intermediate shaft to said turn table shaft. 80 85

5. In a phonograph motor having a winding shaft, a turntable shaft substantially in a plane through said winding shaft, and a supporting frame, a three-point suspension 90 therefor having one point substantially in said plane and the other two points arranged substantially symmetrically with respect to said plane.

6. In a phonograph motor having a winding shaft, a turntable shaft, and a supporting frame, a three point suspension for said frame arranged substantially symmetrically with respect to said shafts. 95

7. A suspension as in claim 5, wherein the 100 points of suspension all lie substantially outside the lateral limits of said motor.

8. A phonograph motor comprising a spring, winding means for tensioning said spring, a drive shaft arranged to be driven by said spring, a turn table shaft disposed at substantially right angles to said driving shaft, an intermediate shaft disposed at a substantial angle to each of said shafts and lying substantially parallel to the plane determined by said shafts, a sliding and rolling connection transmitting rotation from said drive shaft to said intermediate shaft, and a sliding and rolling connection transmitting rotation from said intermediate shaft to said 110 turn table shaft. 115

9. A phonograph motor comprising a spring motor, a drive shaft associated therewith and driven thereby, a turntable shaft disposed at a right angle to the drive shaft, 120 an intermediate shaft disposed at an oblique angle to both of said shafts, a pair of gears operatively connecting the drive shaft and the intermediate shaft, and a pair of gears operatively connecting the turntable shaft 125 and the intermediate shaft, the two gears of each pair having faces of substantially equal widths.

10. A phonograph motor comprising a spring motor, a drive shaft driven thereby, 130

a turntable shaft disposed at a right angle to the drive shaft, an intermediate shaft disposed at substantially equal oblique angles to both said first-mentioned shafts, a pair of spiral gears operatively connecting the drive shaft and the intermediate shaft, and a pair of spiral gears operatively connecting the intermediate shaft and the turntable shaft, the two gears of each pair having faces of substantially equal widths.

11. A phonograph motor comprising a spring motor, a drive shaft driven thereby,

a turntable shaft, an intermediate shaft disposed at an angle of substantially 45° to each of said first-mentioned shafts, a pair of narrow face spiral gears operatively connecting the drive shaft and the intermediate shaft, and a pair of narrow face spiral gears operatively connecting the intermediate shaft and the turntable shaft.

15
20
In testimony whereof, I have signed my name to this specification this fifth day of May 1919.

LOUIS D. NADEL.
